ATTORNEY

UNITED STATES PATENT OFFICE.

HARRY A. STOCK, OF STEELTON, PENNSYLVANIA, ASSIGNOR OF TWO-THIRDS TO
WILLIAM J. MARTIN, OF STEELTON, PENNSYLVANIA.

PROCESS OF AND APPARATUS FOR TEMPERING METALLIC TUBES, TUBULAR CONTAINERS, AND SHEETS.

1,418,986.

Specification of Letters Patent. Patented June 6, 1922.

Application filed February 15, 1921. Serial No. 445,113.

To all whom it may concern:

Be it known that I, HARRY A. STOCK, a citizen of the United States, residing at Steelton, in the county of Dauphin and State of Pennsylvania, have invented new and useful Improvements in Processes of and Apparatus for Tempering Metallic Tubes, Tubular Containers, and Sheets, of which the following is a specification.

10 One object of my present invention is the provision of a process for economically, accurately and thoroughly tempering tubes, tubular containers and sheets or plates, as well as other metallic articles which are ordinarily subjected to the tempering operation.

Another object of the invention is the provision of improved and materially advantageous means for carrying out the process.

20 To the attainment of the foregoing, the invention consists in the improvement as hereinafter described and definitely claimed.

In the accompanying drawings, forming part hereof:—

25 Figure 1 is a transverse section of an apparatus for tempering bottles, containers or tubes in accordance with my invention.

Figure 2 is a similar view of a modification for the same purpose.

30 Figure 3 is a transverse section of a modification for tempering metallic sheets or plates in accordance with my invention.

The chief characteristic of my invention resides in the interposition of a heat collecting medium between a cooling or tempering means and the article that is being tempered, the said medium serving to isolate the cooling or tempering means from the article that is being tempered and also serving by virtue 40 of its conductivity to take heat from the article that is being tempered and give off such heat to the cooling or tempering means.

In Figure 1 of the drawings the apparatus includes a tank 1 for the cooling or tempering means 2 which may be water or any other appropriate agent. Water is introduced into the tank 1 through a pipe 3, and water is discharged from the said tank through a pipe 4, equipped with a relief valve 5—i. e., a valve adapted to open under a predetermined pressure so as to permit water to pass from the tank 1 and also with a view to maintaining a certain predetermined pressure in the tank 1.

The tubular article 6 shown in position 55 to be tempered may obviously be a metallic container such as a bottle, or may be a pipe or any other tubular article. In order to be tempered the said article 6 is positioned as illustrated in the conductive medium 7 for 60 collecting or taking heat from the article 6 and giving off such heat to the cooling or tempering means 2. The said medium 7 is preferably formed of copper, though I would have it distinctly understood that it 65 may be formed of any other material compatible with its defined function without involving departure from the scope of my invention as claimed. Said medium 7 is contractible under the pressure of the means 70 2 in the tank 1, and is also expandible when relieved of pressure. It comprises a circular portion 7^a made up of arcuate sections, and flanges 7^b extending outwardly from the ends of the sections 7^a and connected together at 7^c so that the several sections 7^a 75 form a circular series.

Manifestly an article such as the article 6 may be readily introduced into the medium 7, and when it is so introduced an operator 80 may, by controlling the pressure of the means 2 in the tank 1, accurately regulate the pressure that the medium 7 exerts against the article 6 with the result that the tempering may be nicely governed by the 85 operator as regards the beginning and ending and the duration of the tempering.

In the modification shown in Figure 2 the tank for the cooling or tempering means 2 is in two sections 1^a, which are appropriately 90 fixed with respect to each other and are provided with inlet and outlet pipes 3 and 4 for water or other cooling or tempering agent and have their opposed walls formed by heat collecting medium 7^w, preferably 95 copper. Each of the said mediums or walls 7^w is provided with an intermediate arcuate portion 7^x, and the two portions 7^x are relatively arranged as illustrated in order to receive between them a tubular article 6 to be 100 tempered.

It will be apparent that by controlling the pressure of the means 2 in the tanks 1^a an operator is enabled to crowd the portions 7^x of the mediums 7^w against the tubular article 6 to a greater or less extent as different conditions require.

The embodiment shown in Figure 3 is for

the tempering of sheets or plates one of which is shown and numbered 6^a. The said embodiment is similar to that shown in Figure 2 except that the conductive heat collecting medium 7^v, preferably of copper, are flat in form. The operation of this embodiment, however, is generally similar to that of the embodiment shown in Figure 2.

It will be apparent from the foregoing 10 that in the several embodiments illustrated a heat collecting medium in contact with the article to be tempered serves to take heat from the said article and also serves to give off such heat to the cooling or tempering 15 means while keeping such means out of direct contact with the article to be tempered. It will also be apparent that in each and all of the said embodiments the cooling or tempering means is employed as an elastic medium 20 for initiating and ending the pressure of the heat collecting medium against the article to be tempered as well as controlling the degree of pressure maintained against such article.

25 Having described my invention, what I

claim and desire to secure by Letters-Pat-
ent, is:—

1. The process of tempering metallic arti-
cles which consists in interposing a conduc-
tive medium between an article to be tem-
pered and an elastic cooling or tempering
means and utilizing the elastic cooling or
tempering means for the regulation of the
pressure that the said medium exerts against
the article to be tempered. 35

2. Means for tempering metallic articles,
comprising closed containing means for
elastic cooling or tempering means, and sec-
tional conductive means carried by said con-
taining means to segregate the cooling or 40
tempering means from the article to be tem-
pered and to take heat from said article and
give off the heat to the cooling or tempering
means; the said sectional conductive means
being subject to pressure of the elastic cool-
ing or tempering means in opposite direc-
tions against an article to be tempered. 45

In testimony whereof I affix my signature.

HARRY A. STOCK.
